UNITED STATES PATENT OFFICE.

ALEXANDER B. TAPPEN, OF OSSINING, NEW YORK.

REINFORCEMENT FOR CONCRETE COVERINGS.

1,210,560.

Specification of Letters Patent. Patented Jan. 2, 1917.

Application filed June 18, 1913. Serial No. 774,308.

To all whom it may concern:

Be it known that I, ALEXANDER B. TAPPEN, a citizen of the United States, and a resident of Ossining, in the county of Westchester and State of New York, have invented certain new and useful Improvements in Reinforcements for Concrete Coverings, of which the following is a specification, reference being had to the accompanying drawings, forming a part thereof.

My invention relates to reinforcements for concrete and other composition coverings of structural members such for example as steel beams.

One object of my invention is to provide a reinforcement of the character above indicated that shall be relatively compact as an article of manufacture and that shall be adapted to be expanded when it is put into service.

Another object is to embody in such a reinforcement, means for either spacing the parts of a mold in which the concrete is to be formed from the structural member in order to determine its position relative thereto or to positively secure the mold in position or for performing both of these functions.

Other objects and advantages of my invention will be set forth hereinafter.

I will describe my invention in the following specification and point out the novel features thereof in appended claims.

Referring to the drawings, Figure 1 is a transverse sectional elevation of the lower part of a beam to which a reinforcement in its contracted state as manufactured, is applied. A corresponding view of the I-beam with the reinforcement expanded, is shown in Fig. 2 together with a portion of the mold which is assembled about the beam. The projections of the reinforcement which serve to space the members of the mold from the beam are clearly shown. Fig. 3 is a view corresponding to Fig. 2 except that the sectional view is taken so as to clearly show the parts of the reinforcement which hold the members of the mold in position. A bottom plan view of the beam of the other figures is shown in Fig. 4, a portion of the reinforcement being expanded and a portion being shown in a contracted form. This view clearly illustrates the lateral contraction of the reinforcement when it is ex-

panded longitudinally. Fig. 5 is an isometric perspective of a portion of the reinforcement shown in the other figures.

Like characters of reference designate corresponding parts in all the figures.

The reinforcement of my invention comprises a series of cross stays or members which are so connected that the reinforcement is capable of being expanded longitudinally of the beam or structural member to which it is applied and of being contracted laterally thereof, the cross stays or members of the reinforcement being provided with attaching projections which hook over the flanges of the beam or structural member when the reinforcement is longitudinally expanded. The extent of longitudinal expansion and lateral contraction are both limited by the width of the flange to which the reinforcement is applied.

The projections which hook over the flanges of the structural member, are so arranged as to properly space the cross stays from the adjacent surface of the beam in order that they may be embedded to a suitable depth in the concrete or like composition covering which is applied to the beam. The form of the reinforcement may obviously be considerably varied within the spirit of my invention and I intend that only such limitations be imposed as are indicated in the appended claims. In the form shown in the drawings, which are intended to illustrate the principles of my invention, without limiting it to any specific structure, each of the cross stays or members 10 is connected near its respective ends to the adjacent cross stays of the series at opposite sides. In its contracted form, and as manufactured, the stays are close together and are parallel to each other as shown near the top of Fig. 4. On the other hand a zig-zag structure is produced when the reinforcement is expanded as shown in the lower part of Fig. 4 and in Fig. 5. Any suitable means may be employed for securing the cross stays 10 to each other, but I prefer to weld an attaching piece 11 at each point of connection as shown in the drawings.

By welding the connecting pieces 11 to the wire cross stays, the cross stays are annealed and softened adjacent to the weld

and consequently when the reinforcement is expanded the bends in the wire come at the point of connection and the portion of the cross stays between the points of connection are straight. Another advantage in this arrangement arises from the fact that it is only necessary to exert a pull at opposite ends of the reinforcement in order to expand it uniformly.

10 Beyond the point of connection at one end of each of the cross stays, is an offset projection which is bent inwardly over the cross stay at a suitable distance from it to form an L-shaped hook or socket 12. The 15 other end is extended beyond its point of connection to constitute either a spacing projection 13 (see Fig. 2) or a holding projection 14 (see Fig. 3). The projections 13 and 14 from some of the cross stays are preferably bent at right angles to the cross stay to constitute either spacers 13^a or holding members 14^a. The arrangement of projections is such that the L-shaped hooks or sockets are located alternately at opposite sides of the beam to which the reinforcement is applied and they are so positioned that when the reinforcement is contracted it may be readily applied to the flange of the beam with which it is intended to be used, as clearly shown in Fig. 1. When the reinforcement is expanded, the hooks or sockets are drawn toward the central plane of the beam and consequently the flange fits snugly into the 35 sockets as shown in Figs. 2, 3 and 4.

The arrangement of the spacing and holding projections will be determined by the requirements of each particular case and may be uniform or non-uniform. In fact 40 all of the projections may be spacing projections or all of them holding projections. I prefer however, that they may be arranged somewhat as shown in Fig. 5 a pair of holding projections being located between two unlike sets of spacing projections. It may be found desirable however, in many cases to provide a relatively few spacing projections and a comparatively large number of holding projections.

50 My invention is of course not restricted to a reinforcement formed of iron wire or any other specific material, metal strap or expanded metal being also suitable for this purpose. The form of the reinforcement 55 will depend somewhat upon the form of the structural member to which it is to be applied but anyone skilled in the art will have no difficulty in making such slight variations as are necessary to adapt the reinforcement to a beam of any given cross section.

This invention is an improvement upon the inventions made by David Homer Hayden for which he has applied for Letters 65 Patent, and I do not claim the general idea

of making an expansible reinforcement such as has been disclosed in his applications.

What I claim is:

1. A reinforcement for a molded composition covering of structural members comprising a series of wire cross stays each connected near its respective ends to the adjacent cross stays of the series at opposite sides, the wire beyond one of said points of connection being bent to form a spacing portion and an inwardly facing holding socket, and the wires beyond the opposite points of connection being arranged to form members for spacing and determining the position of the mold in which the composition is to be formed. 70

2. A reinforcement for a molded composition covering of structural members comprising a series of wire cross stays each softened and welded near its respective ends to the adjacent cross stays of the series at opposite sides, the wire beyond one of said points of connection being bent to form a spacing portion and an inwardly facing holding socket, and the wires beyond the opposite points of connection being arranged to form members for spacing and determining the position of the mold in which the composition is to be formed. 85

3. A reinforcement for a molded composition covering of structural members comprising a series of wire cross stays each connected near its respective ends to the adjacent cross stays of the series at opposite sides, the wires beyond one of said points of connection being bent to form a spacing portion and an inwardly facing holding socket comprising an upper holding loop and a lower finger of greater length than that of 105 said loop, and the wires beyond the opposite points of connection being arranged to form members for spacing and determining the position of the mold in which the composition is to be formed. 95

4. A reinforcement for a molded composition covering of structural members comprising a series of wire cross stays each connected near its respective ends to the adjacent cross stays of the series at opposite sides, the wire beyond one of said points of connection being bent to form a spacing portion and an inwardly facing holding socket, the wire of some of the stays beyond the opposite point of connection being arranged to 110 form spacing projections and the wire of others of the stays beyond said opposite point of connection being arranged to extend through the members of a mold in which the composition is to be formed and 120 to be bent over to hold the mold members in desired position. 125

5. A reinforcement for a molded composition covering of structural members comprising a series of wire cross stays each sof- 130

tened and welded near its respective ends to the adjacent cross stays of the series at opposite sides, the wire beyond one of said points of connection being bent to form a
5 spacing portion and an inwardly facing holding socket, the wire of the stays beyond the opposite point of connection being arranged to form spacing projections and the wire of others of the stays beyond said 10 opposite point of connection being arranged to

extend through the members of a mold in which the composition is to be formed and to be bent over to hold the mold members in desired position.

In witness whereof, I have hereunto set my hand this 17 day of June, 1913.

ALEXANDER B. TAPPEN.
